SPEED INDICATOR

William H. Harstick, Richmond, Ind., assignor to
International Harvester Company, a corpora-
tion of New Jersey

Application July 10, 1940, Serial No. 344,741

4 Claims. (Cl. 116—74)

The present invention relates to improvements in an audible speed indicator for a cream separator.

It is desirable, when operating a cream separator by hand, to have a speed indicator which will indicate the R. P. M. of the driving shaft, since the milk and cream are properly separated only when the separator is run at a certain speed. It is also desirable to have the separator streamlined and with as few parts projecting therefrom as possible, so that the separator may be easily cleaned.

It is, therefore, an object of the present invention to provide an enclosed speed indicator for a cream separator.

Another object of the invention is to incorporate a speed indicator in a standard part of the separator.

Another object of the invention is to provide a simple and improved device for indicating when a predetermined rate of rotation of a driving shaft has been exceeded.

According to the present invention, the radially extending portion of the crank for a cream separator is provided with a closed end passageway in which there is provided a freely movable body. A combined cover and striking plate is secured over the open end of the passageway.

Other objects and advantages of the present invention will appear from the following description taken in connection with the accompanying drawing, in which:

Figure 1 is a side view of a cream separator with the improved speed indicator provided thereon;

Figure 2 is a sectional view of the crank, showing the improved speed indicator with the movable body at the end of the passageway; and,

Figure 3 is a sectional view of the crank, showing the improved speed indicator with the movable body in contact with the combined cover and striking plate.

Referring now to Figure 1, there is shown a cream separator 10 which has a horizontally extending driving shaft 11 which, when driven, drives the cream separator in the usual manner. At the end of the shaft 11 is mounted a crank 12 which includes a horizontal portion 13, a radially extending integral arm 14, and a handle portion 15. The horizontal portion 13 is provided with a closed end bore 13a in which the driving shaft 11 is fitted. A set screw 16 secures the portion 13 to the shaft 11. Said screw has a boss 16' fitting radially into a kerf 11' cut into the shaft 11, as shown.

The speed indicator is provided within the radially extending integral arm 14 of the crank 12. A passageway or bore 17 extends past the closed end bore 13a and lengthwise a substantial distance into the arm 14. A movable body, such as a free ball weight 17a, is provided within the passageway 17. At the open end of the passageway 17 and adjacent the horizontal portion 13 there is formed a boss 18, over which a combined striking plate and cover 19 is press-fitted. As shown in Figures 2 and 3, the cover 19 is also spaced from the end of the boss 18. By having the combined striking plate and cover 19 press-fitted over and spaced from the end of the boss 18, the cover 19 is placed in tension, so that, when the movable body 17a strikes the cover, a clear audible sound is emitted.

Referring to Figure 2, the movable body 17a is shown at the end of the passageway 17. As the crank 12 is rotated over the top half of its cycle of revolution about the axis of the shaft 11, the movable body 17a falls by gravity from the end of the passageway 17, down the passageway toward the axis of the shaft 11, and strikes the combined striking plate and cover 19 when the crank is in the position shown in Figure 3. The ball 17a falls by gravity to the handle end of the passageway 17 during the bottom half of the movement of the crank. The movable body 17a falls by gravity between the end of the passageway 17 and the cover 19 on each revolution until the crank is rotated at such a speed that the movable body does not have time to fall by gravity and strike the cover 19. When the desired speed has been reached, the movable body is held at the end of the passageway by centrifugal force and by the short interval of time in the change of positions of the crank.

From the foregoing description, it will be seen that a simple and improved speed indicator has been provided. The crank for the separator has no projections extending therefrom. The speed indicator is completely enclosed within the crank 12, and the cover 19 serves to enclose the passageway and also serves as a striking plate. By this design the outside of the crank can easily be cleaned.

It is the intention to limit the invention only within the terms of the appended claims.

What is claimed is:

1. A manual operating means and speed indicator for cream separators having a horizontal driving shaft comprising a crank that consists of an arm having a horizontal portion at one end and a handle at the other end, said horizontal

portion having a bore adapted to fit the driving shaft, said arm having a passageway extending lengthwise therein throughout the major portion thereof, a weight located in said passageway for free movement therein, and a combined striking plate and cover secured over the open end of said passageway in spaced relation to the said end of said passageway to cause the plate to emit a sharp click when the weight strikes same but disposed in sealing relationship to the arm to prevent ingress of dirt into the passageway and also to result in an arm having a surface contour free of obstructions.

2. A manual operating means and speed indicator for cream separators having a horizontal driving shaft comprising a crank that consists of an arm having a horizontal portion at one end and a handle at the other end, said horizontal portion having a closed end bore adapted to fit the driving shaft, said arm having a passageway extending from the horizontal portion past the closed end bore lengthwise therein through a major portion of the arm, a weight located in said passageway for free movement therein, and a combined striking plate and cover secured over the open end of said passageway in spaced relation to the said end of the passageway to cause the plate to emit a sharp click when the weight strikes same but disposed in sealing relationship to the arm to prevent ingress of dirt into the passageway and also to result in an arm having a surface contour free of obstructions.

3. A manual operating means and speed indicator for cream separators having a horizontal driving shaft comprising a crank that consists of 35

an arm having a horizontal portion at one end and a handle at the other end, said horizontal portion having a closed end bore adapted to fit the driving shaft, said arm having a passageway

5 extending from the horizontal portion past the closed end bore lengthwise therein, a weight located in said passageway for free movement therein, and a combined striking plate and cover spaced from and secured over the open end of said passageway in a manner to be hit substantially at its center by the weight, said cover having sealing relationship to the passageway to prevent ingress of dirt and present an arm having a smooth outer contour free of obstructions.

10 15 4. A manual operating means and speed indicator for cream separators having a horizontal driving shaft comprising a crank that consists of an arm having a horizontal portion at one end and a handle at the other end, said horizontal portion having a closed end bore adapted to fit the driving shaft, a boss extending from said horizontal portion near its juncture to said arm, said arm having a passageway extending from the boss on the horizontal portion past the closed end bore lengthwise therein, a freely movable weight located in said passageway, and a combination striking plate and cover adapted to be press-fitted over said boss in sealing relationship thereto to prevent ingress of dirt into the passageway but spaced from the boss so that when the cover is hit by the weight a sharp sound is emitted and the arm presents a smooth outer surface contour free of obstructions.

WILLIAM H. HARSTICK.
